UNITED STATES PATENT OFFICE.

ERNEST KIRCHHOFF, OF GREAT RILLS, NEW YORK, ASSIGNOR TO ELIAS REISS AND COMPANY, OF NEW YORK, N. Y., A CORPORATION OF NEW YORK.

DESIGN FOR TEXTILE FABRIC.

Application filed March 8, 1927. Serial No. 21,062. Term of patent 3½ years.

To all whom it may concern:

Be it known that I, ERNEST KIRCHHOFF, a citizen of the United States of America, residing at Great Rills, in the county of Richmond and State of New York, have invented a new, original, and ornamental Design for Textile Fabric, of which the following is a specification, reference being had to the accompanying drawing, forming a part thereof.

The drawing is a face view of a piece of textile fabric showing the new design.

I claim:

The ornamental design for textile fabric, as shown.
